(57) **CLAIM**

The ornamental design for a multilayered rainbow tealight candle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a multilayered rainbow tealight candle showing my new design; and,

FIG. 2 is a perspective view of the second embodiment thereof, wherein the colors of the wax appear in reverse of FIG. 1.
